(57) **CLAIM**

The ornamental design for a merchandising fixture, as shown and described.

DESCRIPTION

FIG. 1 is a view in perspective of a merchandising fixture. FIG. 2 is a front plan view of the merchandising fixture of FIG. 1.

FIG. 3 is a rear plan view of the merchandising fixture of FIG. 1.

FIG. 4 is a top view of the merchandising fixture of FIG. 1.

FIG. 5 is a bottom view of the merchandising fixture of FIG. 1; and,

FIG. 6 is a side view of the merchandising fixture of FIG. 1. The broken lines shown are for illustrative purposes only and form no part of the claimed design.
